UNITED STATES PATENT OFFICE

133,107

DESIGN FOR AN ADJUSTABLE-LENGTH WINDOW CORNICE

Elmer F. Rebholz, Chicago, Ill.

Application January 23, 1941, Serial No. 98,304

Term of patent 7 years

To all whom it may concern:

Be it known that I, Elmer F. Rebholz, a citizen of the United States, residing at Chicago, county of Cook, and State of Illinois, have invented a new, original, and ornamental Design for an Adjustable-Length Window Cornice, of which the following is a specification, reference being had to the accompanying drawing, forming a part thereof, in which:

Figure 1 is a perspective view of an adjustable-length window cornice showing my new design; Fig. 2, a top plan view of the same; and Fig. 3 is a perspective view of the bracket used

in securing the end portions to the body of the cornice.

The present design is characterized by a window cornice having a centrally positioned front strip member, the ends of which are secured by a pair of flush, close-fitting end brackets to a pair of adjustable equal width arcuate end members, all as shown.

I claim:

The ornamental design for an adjustable-length window cornice, as shown and described.

ELMER F. REBHOLZ.
